APPARATUS FOR MAKING STAMPS

Helge S. Jonsson, Villa Park, Ill.

Application June 7, 1941, Serial No. 397,143

2 Claims. (Cl. 101—4)

My invention relates to the method of making stamps or dies, as well as apparatus for making stamps, such as printing stamps, punches, type wheels and the like.

The invention has among its objects an improved economical method or process of making such devices, as well as an improved apparatus which is simple, efficient, durable, which may be inexpensively manufactured and economically operated.

The invention has particularly as an object the production of an apparatus which will direct a light weight projectile provided with a die or matrix at very high velocity against a blank. It is the purpose of the apparatus to discharge and direct the matrix carrying projectile against the die blank in such a manner as to form a clear, sharp impression on the blank without in any way injuriously distorting the blank other than distorting to form the impression thereon.

The invention has as an object the production of an apparatus in which the matrix carried by the projectile strikes the blank but once rather than with a plurality of successive blows, and differs from any other apparatus that is known to me in that it employs a very light projectile rather than a heavy weight, the travel of the projectile being somewhat similar to the travel of a light weight bullet discharged from a rifle.

Many other objects and advantages of the construction herein shown and described will be obvious to those skilled in the art from the disclosure herein given.

To this end my invention consists in the novel construction, arrangement and combination of parts herein shown and described, and more particularly pointed out in the claims.

In the drawings, wherein like reference characters indicate like or corresponding parts:

Fig. 1 is a view in elevation of one form of my apparatus with portions broken away to show the construction;

Fig. 2 is a side elevation of the same;

Fig. 3 is a view in section illustrating a portion of the apparatus shown in Fig. 1;

Fig. 4 is a vertical section substantially as Fig. 3 but revolved ninety degrees with respect thereto.

Fig. 5 is a perspective view of the projectile or matrix carrier shown in Fig. 3;

Fig. 6 is a perspective view of a portion of a stamp as formed by the apparatus;

Fig. 7 is a perspective view of a portion of the blank prior to forming the character thereon; and

Fig. 8 is a perspective view of a modified form of projectile.

Referring to the drawings, first to Figs. 5 and 6, 1 represents a stamp or die as formed, 2 being the character formed at one end thereof. This impression of the desired character is formed by means of a matrix or die 3 bearing the character to be reproduced.

Referring now to Figs. 1 and 2, 11 represents a frame which is provided with a base portion 12 adapted to be supported by the legs 13. The frame is provided with a head 14 at the end which carries a blank holder for the blanks 1' as will be hereinafter described.

15 Arranged in the frame is what may be termed a barrel 15, the lower end of which is secured in a centering plate 16 secured to the base plate 12 by studs 17 or in an equivalent manner. As shown, the plate 12 is provided with an opening 19 therethrough and the member 16 with a depending portion 18 extending through the opening 19. The upper end of the barrel 15 extends through a sleeve 21 which is carried by the part 20 on the frame, the same being centered and 25 held firmly in place by means of set screws 22 or their equivalent.

Arranged within the barrel is the projectile 24. Where the projectile is cylindrical in shape I prefer to provide a key 25 and groove the interior 30 of the barrel as indicated at 26 so that the projectile cannot rotate within the barrel during its travel, but is always presented to the blank in the same position.

Arranged at the lower end of the barrel and 35 carried by the portion 18 of the plate 16 is a valve casing or housing 27 which is provided with the extension portion 28 threadedly engaging in the part 18. Within the bore of the housing 27 is arranged a valve 29 provided with passage-ways 31 which may be brought into registry with the ports 32 and 33 in the housing 27. Port 33 communicates with the interior of the barrel 15, while port 32 communicates with the storage tank or receptacle 35, constituting an 40 air reservoir for containing compressed air which 45 may be supplied through a pipe 36 or the equivalent. There is also provided a suction pipe 37 communicating with the interior of the housing through which air from the interior of the barrel 50 may be drawn out when the projectile has traveled outwardly from the valve housing and carried the matrix or die to the blank to be formed and the air pressure from the air reservoir 35 has been shut off.

55 The valve 29 is a quick acting valve, that is to

say, it opens quickly to admit a shot of air under high pressure to the barrel and thereafter quickly shuts to relieve the pressure on the projectile. While any suitable valve mechanism may be employed for the purpose, I have illustrated valve 29 provided with a stem 39 which projects through the housing cover plate 30 at one end of the housing and is secured to a valve operating arm 40. As shown, a bracket 38 is carried by the base 12, this bracket being recessed to receive the arm 40 secured to the shaft 39 by a pin 41 or the equivalent. The free end of the arm 40 is connected to a bracket 45 by means of a spring 44. The bracket 38 is provided with stops 42 and 43 for the arm, the arrangement being such that when the arm is in the position shown in Fig. 1 the valve is closed. The arm 45 is mounted on the shaft 46 and connected through a link 47 to a foot pedal lever 50 at 49. A spring 53 arranged between a collar 54 on the rod 46 and the base 12, tends to normally maintain the rod and arm 45 as shown in Fig. 1. When the foot pedal lever 50 is depressed, arm 45 moves downwardly past the end of 39, and as soon as it passes the dead center, the spring 44 tends to snap the valve into its open position, discharging the air under pressure to the barrel 15 whereupon the projectile is shot outwardly at high velocity. As soon as the projectile is shot, the foot pedal 50 may be released and the rod 46 is thereby released automatically through the action of spring 53 causing the return of the pedal, and rod 46 is then permitted to move upwardly, carrying with it the arm 45. The valve arm 40 is thereupon again moved past the dead center and the valve snaps shut the passage to the tank or reservoir 35, so that the interior of the barrel is open to suction pipe 31, or atmosphere. It is preferred to snap the valve shut substantially about the time the projectile passes the port 75 hereinafter referred to. Due to suction and gravity, the projectile in the meantime has dropped down to the position shown in Figs. 3 and 4.

Carried by the head 14 of the frame is a shaft 55 which carries a blank holder 56 which is preferably rotatable with the shaft. The blank holder 56 is provided with the extended portions 57 in which the blanks 1' may be positioned. The turret or chuck 56 carrying the blanks may be turned manually, as shown, or in any other suitable manner. In order to align the blank with the projectile, I have shown a plate 58 secured to the shaft 55, the same being provided with an opening 59 for each blank holder. The rod 46 is connected at 65 to an arm 62 pivotally secured on the frame at 63. The end is bifurcated and receives a pin 64 on a small rod 60 carried by the bracket 61. When the foot pedal lever 50 is depressed the rod 60 is raised, engaging the member 58 in one of the holes 59, locking the chuck or turret against movement while the lever is depressed and the stamp being formed.

I have shown at the outer end of the barrel 15 a cap 67 and gasket 68, the cap being provided with an opening 69 of a size to permit the matrix 3 to pass therethrough when the valve is opened and the projectile thrown outwardly to bring the matrix into engagement with the blank. I have also shown in Fig. 3 a port 75 arranged in the barrel to provide a vent for releasing the air at that point when the projectile is thrown outwardly in the barrel, so that the air pressure is substantially off of the projectile at the time of impact, the blow being brought about by the

momentum of the projectile, rather than air pressure at the moment of impact.

The method of forming the blanks and the operation of the apparatus as illustrated may be briefly described as follows: Assuming that the proper matrix has been applied to the projectile or matrix carrier 24 which is arranged in the barrel 15, and there is air pressure in the reservoir 35 with the valve 29 closed and a blank 1' arranged in the blank carrier 57, as shown in Fig. 1: The pedal lever 50 is depressed. As rods 47 and 46 are moved downwardly, the arm 45 moves downwardly (see Fig. 1) and this carries the end of the spring 44 secured thereto downwardly. At the same time the locking rod 60 moves upwardly to engage in the opening or hole 59 in the plate 58. When the arm 45 has been moved downwardly sufficient to cause the spring 44 to pass the valve stem 39, as it passes the dead center the arm 40 is immediately snapped down under the pull of the spring 44, turning the valve 29 and admitting air to the barrel 15 under high pressure. The pressure on the projectile 24 causes the same to travel outwardly the barrel at a high velocity, carrying with it the matrix 3 and striking the blank 1'. As soon as the projectile passes the port 75 the air pressure below the projectile is relieved, but the momentum of the projectile causes it to strike the blank with the matrix, forming the character or design on the end of the blank. The striking of the blank by the matrix at high velocity with the light projectile does not deform the blank in the manner the dropping of a heavy weight on the blank would distort the body of the blank, nor in the same manner that repeated blows would distort the body of the blank. To the contrary, the body of the blank generally is not particularly distorted, but the imprint of the matrix is sharply defined on the blank and appears clean-cut. The pressure on the pedal being released, obviously, by means of the spring 53, the valve is closed, and in the construction illustrated the interior of the barrel is then open to suction through port 33 and the valve ports 31 which communicate with the suction line 31 or to the atmosphere, so that the projectile drops back to the position shown in Fig. 3. Without the suction, however, gravity would tend to draw it back, as the weight of the projectile, although light, would be sufficient to cause it to return to the closed end of the barrel.

After the blank has been formed into a stamp 1, as shown in Fig. 6, the stamp may be removed from the holder 57 and suitably heat-treated to harden the same. I have found that by employing this light weight projectile and impelling it at high velocity, there is no tendency to fold over the material in the blank or to so affect the structure of the blank material as to weaken the same.

In Fig. 8 I have illustrated a modified form of projectile. In the form shown in Fig. 5 the projectile or matrix or matrix carrier is made cylindrical to fit in a cylindrically bored barrel. Obviously, the barrel may be square or of an irregular cross section so that the projectile will not tend to rotate or turn in the barrel. Fig. 8 shows a square projectile 71 provided with the matrix 70 formed as a part of the projectile. Various other modifications may be made in the projectile or carrier, the matrix or the barrel.

Having thus described my invention, it is obvious that various immaterial modifications may be made in the same without departing from the

spirit of my invention; hence I do not wish to be understood as limiting myself to the exact form, construction, arrangement and combination of parts herein shown and described, or uses mentioned.

What I claim as new and desire to secure by Letters Patent is:

1. In an apparatus for forming steel stamps or the like, a frame, a tubular barrel arranged thereon, said barrel open at one end and closed at the other, said barrel provided with a fluid inlet adjacent the closed end, means for supplying a fluid under high pressure through the said port, a valve for controlling the admission of fluid to the port, actuating means for controlling the valve, a projectile arranged in the barrel between said port and the open end thereof, said projectile provided with a design at the outer end thereof, a stamp blank holder mounted on said frame adjacent the outer end of the barrel for rigidly holding a face of the stamp blank in proximity to the open end of the barrel in the path of the projectile, and means cooperating with said valve actuating means for locking the said holder in operative position.

2. In a stamp forming machine of the kind described, a frame provided with a tubular barrel open at one end and a relief vent spaced back from the end and provided with an inlet port at the other end, means for supplying a fluid under pressure through said port, a valve for controlling the admission of fluid through the port to the interior of the barrel, valve actuating mechanism including resilient means for controlling the valve and to snap the same open and shut as desired, a projectile arranged within the barrel between the ends thereof and movable from the closed end of the barrel toward the opposite end thereof, said projectile provided on its outer end with a suitable design corresponding to a negative of a design to be formed on a stamp blank, and a stamp blank holder arranged in proximity to the outer open end of the barrel for rigidly holding the stamp blank in the path of the projectile and presenting a face upon which the design is to be formed.

HELGE S. JONSSON.
